ABSTRACT OF THE DISCLOSURE

A packet of sheets having spaced perforations adjacent one edge are bound while the packet is fed along a predetermined path by successively inserting a plurality of strips of binding elements into the perforations. Each binding strip is fed by a drive system including a high speed electrical clutch-brake unit which is controlled by a circuit including a photocell for sensing perforations within the packet and a photocell actuated counter for counting the binding elements.

BACKGROUND OF THE INVENTION

In the binding of packets of perforated sheets as disclosed in U.S. Pat. No. 3,334,918 issued to Pigna et al., a wire binding strip having a plurality of looped prongs and a generally C-shaped cross-sectional configuration is fed into engagement with each packet as the packet is conveyed along an inclined surface. The prongs are extended through the perforations by rotating the strip which is then closed by reciprocating press members located at a closing station.

The feeding of each binding strip is controlled by photocells which sense the leading and trailing edges of the packet. Thus to provide precise alignment between the perforations in each packet and the prongs of its binding strip, it is necessary to have precise predetermined spacing between the leading edge of the packet and the first perforation and also for the binding strip to be fed in precise time relation with the feed of the packet.

It has been found that during the production of the packets, the location of the perforations relative to the leading edge of the packet will frequently vary so that it is difficult to obtain registration or alignment between the prongs of the binding strip and the spaced perforations. Furthermore, it has been found difficult to control the intermittent feeding of the binding strips in timed relation with the spacing and feeding of the packets in order to obtain a high speed, accurate and efficient binding operation.

SUMMARY OF THE INVENTION

The present invention is directed to an improved method and apparatus for successively binding books or packets of perforated sheets in order to obtain a high speed, dependable and efficient binding operation. In accordance with a preferred embodiment of the invention, the packets are successively conveyed at a predetermined constant speed along an inclined supporting surface. A wire binding strip having longitudinally spaced looped prongs is supplied in a continuous length from a spool and is cut into short strips which are intermittently fed into engagement with the packets by an endless belt driven through an electro-mechanical clutch-brake unit.

A photocell is positioned to sense the leading perforation within each packet. A disk includes peripherally

2

spaced slots corresponding to the spacing between the looped prongs and is rotated so that its peripheral speed is the same as the belt speed. Another photocell and counter system counts the slots for indicating the precise movement of the binding strips. The photocells are connected in a circuit which controls the precise alternating operation of the clutch-brake unit which is provided with momentary surges of a high voltage power to provide rapid starting and stopping of the belt which feed the binding strips

In addition to providing a high speed binding operation, the present invention provides for efficiently binding each packet with a plurality of binding strips spaced at predetermined intervals along the perforated edge portion of the packet. That is, the photocell system for sensing the perforations and for sensing the feed of the binding strip enables a plurality of short binding strips to be successively fed into corresponding groups of perforations spaced at intervals along one edge of each packet. This results in the total length of the strip material for binding each packet and thereby reduces the binding cost for each packet.

BRIEF DESCRIPTION OF THE DRAWINGS

FIG. 1 is a fragmentary and somewhat diagrammatic perspective view of binding apparatus constructed in accordance with the invention;

FIG. 2 is another perspective view of a portion of the apparatus shown in FIG. 1;

FIG. 3 is a diagrammatic view illustrating the final step of the binding operation;

FIG. 4 is a perspective view of a book or packet bound in accordance with the invention; and

FIG. 5 is a schematic electrical wiring diagram of the control circuit for operating the apparatus shown in FIGS. 1 and 2.

DESCRIPTION OF THE PREFERRED EMBODIMENT

Referring to FIGS. 1 and 2, the apparatus includes an elongated base 10 having a longitudinally extending inclined top surface 12 which slopes laterally downwardly to a longitudinally extending guide rail 14. A conveyor 15 includes a plurality of parallel spaced endless chains 16 which extend longitudinally below the surface 12, and each chain 16 carries a plurality of spaced flights 17 each being laterally aligned with a corresponding flight on an adjacent chain.

The conveyor 15 is driven at a predetermined constant speed and serves to deliver a series of books or packets 20 along the surface 12 in successively spaced relation and in a direction toward the right as indicated by the arrow shown in FIG. 1. Referring to FIG. 4, each packet 20 includes a pair of cover sheets 22 and a plurality of intermediate paper sheets 24. A row of three spaced groups of perforations 25 is formed within each packet adjacent one edge.

A coil 28 (FIG. 1) of a continuous length of open wire binding strip 30 is supported above the surface 12 by a spool 31 mounted on a shaft 32 rotatably supported by a post 34 secured to the base 10. The spool 31 is intermittently driven by a motor 35 through a belt drive 36. As shown in FIGS. 3 and 4 and in the above Pigna et al. patent, the open wire binding strip 30 has a generally C-shaped cross-sectional configuration and is formed

by integrally connected and parallel spaced looped prongs 40. The binding strip 30 is covered by a tape 42 when the strip is wound on the spool 31 to prevent entanglement or interlocking of the prongs 40. The tape 42 is released from the strip 30 by directing the strip and tape between a pair of counter-rotating brushes 45 which are supported by a bracket mounted on the post 34 and are driven by a motor 47. After the tape 42 is released from the binding strip 30, the tape is separated and wound on a spool 48 driven by a motor 49.

The wire binding strip 30 supplied from the coil 28 is cut into predetermined lengths which are successively fed into engagement with the packets 20 by a mechanism 55 supported by a slightly inclined plate 56 secured to the base 10. The mechanism 55 includes an electromagnetic clutch-brake unit 60 (FIG. 2) which is supported between parallel spaced flanges 61 of a U-shaped bracket 62 secured to the plate 56. The clutch-brake unit 60 includes an input shaft 64 (FIG. 1) and an output shaft 65 (FIG. 2) which supports a pulley 66. An endless flexible belt 70 having inner and outer laterally extending teeth 71, is directed around the pulley 66 and a similar pulley 72 supported by an arm 74 secured to the main support plate 56. The pulley 72 is positioned above the pulley 66 so that the belt 70 has a lower run which extends adjacent a sloping guide rod 75 (FIG. 2) supported by the arm 71 for receiving the wire binding strip 30 extending from the spool 31.

An air cylinder 78 is mounted on the support arm 74 and actuates a cutoff tool (not shown) which cuts the wire binding strip 30 into short sections or strips 80 each having a predetermined number of prongs 40 corresponding to the number of perforations 25 in each group within the packet 20. A disk 85 is also mounted on the output shaft 65 of the clutch-brake unit 60 and has a plurality of peripheral slots 86 (FIG. 5) which are spaced in corresponding relation to the spacing of the prongs 40 on the wire binding strip 30. A photocell 88 is supported adjacent the disk 85 by a bracket 89 secured to the bracket 62, and is positioned to detect the slots 86 as the disk 85 is rotated.

The input shaft 64 for the clutch-brake unit 60 is driven at a continuous predetermined speed by a motor (not shown) positioned under the plate 56 and connected to the shaft 64 by a positive belt drive 92. The motor is also connected by a belt drive 94 (FIG. 2) to a series of three shafts 95 each rotatably supported by a bracket 96 secured to a vertically adjustable L-shaped arm 97 (FIG. 1). A resilient roller 100 is mounted on each shaft 95, and the three rollers are positioned in longitudinal alignment with the belt 70. The rollers 100 are arranged so that after each wire binding strip 80 is fed into engagement with a packet 20 with the prongs 40 in alignment with the correspondingly aligned perforations 25, the rollers 100 press the strip 80 downwardly causing the prongs 40 to extend through the perforations 25.

As each packet 20 advances beyond the rollers 100, the binding strips 80 on each packet 20 engage an elongated rail 102 (FIG. 2) having a longitudinally extending helical slot (not shown) which rotates each section 80 by approximately 90° in a manner similar to that shown in the above Pigna et al. patent. As each packet 20 travels further down the surface 12, it arrives at a closing station where an upper press member 105 (FIG. 3) is reciprocated in relation to a lower press member 106 to close each binding strip 80 to the position illustrated by the dotted lines in FIG. 3.

Referring to the schematic wiring diagram of FIG. 5 showing a preferred electrical control system for the mechanism 55, a transformer T1 converts the main power supply of 220 volt AC to 110 volt AC which is supplied to lines L1 and L2 through a main control switch S1 and a fuse F1. A pilot lamp PL serves as an indicator when lines L1 and L2 are energized.

A transformer T2 provides a 7 volt AC power supply

to a bridge rectifier system B1 which supplies 7 volt DC power across lines L1 and L3 connected through a fuse F2, a switch S2 and a capacitor C1. A transformer T3 provides a 35 volt AC power supply to a bridge rectifier system B2 which supplies 35 volt DC power across lines L1 and L4 connected through a fuse F3 and a capacitor C2.

A variable transformer T4 supplies a low voltage power supply to a lamp LP which is located directly under a photocell P1 encased within a translucent plastic housing 120 having a cylindrical upper end portion 122 which projects upwardly through a hole formed within the surface 12 (FIG. 2) directly under the drive pulley 66 for the feed belt 70. The plastic housing 120 directs the light from the lamp LP upwardly around the photocell P1. When the leading edge of the packet 20 advances across the upper end portion 122 of the housing 120, the light from the lamp LP is reflected to the top sensitive end of the photocell P1. However, when a perforation 25 passes over the upper end portion 122 of the housing 120, there is no reflection of the light to the photocell P1. This sequence of actuation of the photocell P1 produces signals which are amplified by an amplifier A1 to energize a preset counter 125 (FIGS. 1 and 5). The output signal from the amplifier A1 triggers a transistor TR1 which energizes a relay K1 connected to the transistor TR1 through a manual control switch S3.

Energization of relay K1 closes its normally open contacts 1K1 to charge a capacitor C3 within a line 126 connected across the line L1 and a line L5 connected to the counter 125. When a perforation 25 within a packet 20 passes over the photocell P1, there is no reflective light which enters the photocell P1, and the voltage applied to relay K1 drops to a level which deenergizes relay K1 so that its normally closed contacts 2K1 will close causing the capacitor C3, which was charged to a level of 15 volts, to energize a relay K2. Normally open contacts 1K2 of relay K2 are closed thereby energizing relays K3, K4 and K5. The normally open contacts 1K4 of relay K4 hold the relays K3, K4 and K5 in an energized condition.

Energizing relay K3 opens the normally closed contacts 2K3 thereby opening the line to the brake solenoid BR so that the output shaft 65 is free to rotate. Simultaneous energizing of relay K5 causes the normally open contact 1K5 to close and the normally closed contacts 2K5 to open thereby supplying two voltages to the clutch solenoid CL. The first voltage is at a level of 35 volts DC and is supplied from a capacitor C4 which is charged when contacts 2K5 were closed. This high voltage produces rapid acceleration of the clutch 58 so that each wire binding section 80 is quickly fed into engagement with the packet 20 being fed over the photocell P1. When the clutch solenoid CL is energized, the binding strips 80 start to feed and the charge on the capacitor C4 drops to its normal supply voltage of 7 volts.

When a binding strip 80 starts to feed, the photocell 88 begins counting the slots 86 within the disk 85 thereby counting the number of looped prongs 40 which feed into engagement with the perforations 25. Each count registers on the counter 125, and after a present count is reached, a relay K6 is energized by the counter 125. When normally closed contacts 2K6 open, the relays K2, K3, K4 and K5 are deenergized thereby opening the circuit to the clutch solenoid CL by opening contacts 1K5 and energizing brake solenoid BR through its normally closed contacts 2K3. Capacitor C5 provides an initial high voltage of 35 volts to the brake solenoid BR to effect quick actuation of the brake 60 after which the voltage to the brake solenoid BR drops to its normal level of 7 volts.

When relay K6 is energized, its normally open contacts 1K6 close to energize a relay K7, thereby closing normally open contacts 1K7 to energize a solenoid air valve CAV for actuating the cutoff air cylinder 78 which, as mentioned above, cuts the wire binding strip 30 into the sections 80 having a predetermined number of looped

prongs 40. A manual control switch S4 is arranged in parallel with contacts 1K6, and a manually operated reset switch RS provides for resetting the counter 125. Diodes D1 and D2 serve to isolate the higher voltage power in line L4 from the lower voltage power in line L3, and diodes D3 and D4 serve to dissipate the energy in the brake coil BR and the clutch coil CL when they are deenergized.

The preferred values of the capacitor C1-C10 (in mfd.) and of the resistors R1-R13 (in ohms) are as follows:

Capacitors, volts:

C1, 500/50	R1, 1,000
C2, 500/50	R2, 1
C3, .1/200	R3, 1
C4, .1/200	R4, 1
C5, .1/200	R5, 1
C6, .1/200	R6, 25
C7, 3600/150	R7, 25
C8, 3600/150	R8, 300
C9, .1/200	R9, 1.5
C10, .1/200	R10, 1,000
	R11, 1,000
	R12, 27
	R13, 270

Resistors:

From the drawings and the above description, it is apparent that the method and apparatus of the invention provide desirable features and advantages. For example, by providing the clutch-brake unit 60 in the drive for the binding strip feed belt 70 and by controlling the clutch and brake solenoids with the control system (FIG. 5) including the photocell P1 which senses the perforations 25 in each packet 20, the binding strip sections 80 are quickly fed into engagement with each packet 20 with the looped prongs 40 in precise alignment or registration with the perforations 25. It has been found that the apparatus shown in the drawings is capable of binding packets at a rate of at least sixty packets a minute or one packet per second. Furthermore, the combination of the photocell system for sensing the perforations 25 within each packet 20 and the system for counting the prongs 40 enables a plurality of binding strip sections 80 to be fed successively into engagement with each packet 20 at spaced intervals along the perforated edge so that the overall cost of binding each packet is significantly reduced.

The actuation of the clutch-brake unit 60 as described in conjunction with FIG. 5 also provides an important feature of the invention. That is, the initial supply of a higher voltage to the clutch and brake when they are alternately energized, provides for rapid starting and stopping of the feed of the wire binding strip 30 within a time period of .005 second. As a result, each binding strip section 80 is maintained in precise registration with the corresponding perforations 25 of a packet 20 passing over the photocell P1.

While the method and form of apparatus herein described constitute preferred embodiments of the invention, it is to be understood that the invention is not limited to this precise method and form of apparatus, and that changes may be made therein without departing from the scope of the invention.

What is claimed is:

1. Apparatus for binding a succession of packets each having a plurality of sheets with spaced perforations adjacent one edge, comprising means for feeding each packet along a predetermined path in a direction parallel to said edge, means for sensing the position of each packet, means for feeding a plurality of elongated strips of binding elements into engagement with said perforations of each packet at spaced intervals along said edge while said packet is progressing along said path, and control means for operating said feeding means in response to actuation of said sensing means.

2. Apparatus as defined in claim 1 wherein said means for feeding each said strip of binding elements includes

an electric clutch and an electric brake, and means for quickly energizing said clutch and said brake in an alternating manner.

3. Apparatus as defined in claim 2 wherein said clutch and said brake are each normally operated at a predetermined voltage, and means for momentarily supplying a higher voltage to said clutch and said brake to effect rapid initial actuation of said clutch and said brake.

4. Apparatus as defined in claim 1 including means for counting the binding elements of each strip as it is fed into engagement with a packet, and means connecting said counting means to said control means to effect stopping of said feeding means after a predetermined number of binding elements have engaged the packet to cause binding of each packet with a plurality of binding strips spaced at intervals along said edge.

5. Apparatus for binding a succession of packets each having a plurality of sheets with spaced perforations adjacent one edge, comprising means for feeding each packet along a predetermined path in a direction parallel to said edge, means for sensing the leading perforation within each packet, means for feeding a strip of binding elements into engagement with said perforations of each packet as it is fed along said path, means for counting the number of binding elements while feeding the strip, and control means for operating said feeding means in response to actuation of said sensing means and in accordance with a predetermined counted number of binding elements.

6. Apparatus as defined in claim 5 wherein said means for sensing the leading perforation within each packet comprises a photocell, a light source, and means for positioning said photocell and said light source to effect intermittent actuation of said photocell in response to movement of said perforations along said path.

7. Apparatus as defined in claim 6 including means for positioning said light source and said photocell adjacent said path, and means arranging said light source and said photocell to effect reflection by each packet of the light from said light source to said photocell in the absence of perforations.

8. Apparatus as defined in claim 5 wherein the strip of binding elements is supplied from a coil supported by a spool and is covered by a protective tape to prevent interlocking of the binding elements, and including a set of rotary brush members positioned to receive the binding strip therebetween, and means for rotating each said brush member in a direction opposite to the feed of the binding strip for releasing the protective tape from the strip.

9. An improved method of binding a packet of sheets having spaced perforations adjacent one edge, comprising the steps of feeding the packet along a predetermined path at a substantially constant speed in a direction parallel to said edge, successively feeding a plurality of longitudinally spaced elongated strips of binding elements into engagement with the packet at spaced intervals along said edge while the packet is progressing along said path, extending said binding elements of each said strip through the corresponding said perforations as the packet is fed along said path, and closing said elements of each said strip.

10. An improved method of binding a packet of sheets in a direction parallel to said edge, sensing the leading perforation within the packet, feeding an elongated strip of binding elements into engagement with the packet in response to said sensing of said leading perforation, counting the number of binding elements while feeding the strip, controlling the feeding of the strip in accordance with the counted number of binding elements, extending said binding elements through said perforations as said packet is fed along said path, and closing said elements.

11. A method as defined in claim 10 including the step of successively feeding a plurality of longitudinally spaced strips into engagement with each said pack while

the packet is progressing along said path to effect binding of each said packet with a plurality of said strips located at spaced intervals along said edge.

12. A method as defined in claim 11 including the step of counting the number of binding elements while feeding each strip, and controlling the feeding of each strip in accordance with the counted number of binding elements.
